UNITED STATES PATENT OFFICE.

WILLIAM MAIN, OF BROOKLYN, NEW YORK.

ELECTRIC TELEPHONE.

SPECIFICATION forming part of Letters Patent No. 244,638, dated July 19, 1881.

Application filed January 5, 1881. (Model.)

To all whom it may concern:

Be it known that I, WILLIAM MAIN, a citizen of the United States, residing in Brooklyn, in the county of Kings and State of New York, have invented certain Improvements in Electric Telephones, of which the following is a specification.

This invention relates chiefly to a battery transmitting-telephone. Its object is to provide a telephone which is exquisitely sensitive to vocal sounds uttered in its vicinity without being affected by the extraneous vibrations so frequently occurring coincidently with speech, and which shall transmit or reproduce speech faithfully and without change of tone.

In the accompanying drawings, Figure 1 is a side elevation of my telephone, the inclosing-case being in section taken in the plane of the dotted line 1 1 in Figs. 3 and 4. Fig. 2 is a similar view, the entire telephone being in section, taken in the line 2 2 in Figs. 3 and 4. Fig. 3 is a front elevation of the telephone, the case being in section on the line 3 3 in Figs. 1 and 2; and Fig. 4 is a rear elevation, the case being in section on the line 4 4 in Figs. 1 and 2. The remaining figures illustrate modifications. Fig. 5 is a vertical mid-section corresponding to Fig. 4 and taken on the line 5 5 in Fig. 6. Fig. 6 is a rear elevation with the case in section on the line 6 6 in Fig. 5. Figs. 7 and 8 are horizontal sections in the plane of the line 7 8 in Figs. 5 and 6, illustrating two different methods of making circuit-connections, the inclosing-case being omitted; and Fig. 9 shows another modification, the elements of the telephone being in side elevation and the circuit-connections being illustrated diagrammatically.

As is what I shall hereinafter term an "acoustic vibrator," answering to what in other telephones is called the "diaphragm," so hung as to be capable of a bodily swinging or back-and-forth movement, whereas diaphragms have invariably been tightly clamped or otherwise confined at their edges or elsewhere, so that they could vibrate only within themselves, the inflexibility resulting from their confined attachment tending to suppress, and their own inherent elasticity tending to modify their proper vibration, and prevent them from accu-

rately responding to the form of the sound-wave affecting them.

I mount my vibrator by suspending it flexibly at its upper edge, or from above, leaving it free to vibrate over its entire surface, and to swing bodily to and fro. I leave its edges entirely free to vibrate except at the point or points of attachment or suspension instead of confining them or muffling them, as has been commonly heretofore done. It may be made of any resonant or vibratory material, such as those commonly employed for telephone diaphragms; but I find wood of a resonant quality preferable to any other material that I have tried, inasmuch as it responds to sound-waves more amply than others, (owing partly, perhaps, to its greater lightness,) and consequently transmits a louder sound, and it also has the property of transmitting sounds of different pitch more equally than other materials with which I have experimented.

I prefer that the vibrator be in the form of a flat plate or board, as this is the form by which I have secured the best results; but it may be given other shapes without material detriment to its operation—such, for instance, as a hollow cone or the segment of a hollow sphere. Instead of its being arranged to stand in a vertical plane it may be inclined backward or forward, resting, when used in a battery-transmitter, on the resistance-varying contacts. These modifications, however, are merely possible. I do not consider them desirable.

In order to confine the sound-waves which approach the vibrator and direct them onto its surface, I employ walls or partitions B, arranged at the front side of the vibrator and standing at substantially right angles to its surface. These walls are preferably attached to and borne by the vibrator, as shown in Figs. 1 to 4; but they may be otherwise supported out of contact therewith, as shown in Fig. 5. These walls may consist of a simple rim surrounding the vibrator, or they may be partitions or ribs crossing the same, or, as I prefer, both forms may be used together, as shown in Figs. 1, 2, and 3. These walls serve to collect the sound-waves and guide them against the vibrator, serving, in this respect, a somewhat

similar purpose to the ordinary concave mouth-piece, except that in reflecting the sound they do not concentrate it at one point or focus. When fixed to the vibrator they also, to a great extent, prevent it from responding to inaudible vibrations, thus suppressing microphonic effects, and they also serve to suppress the natural or sympathetic tone of the vibrator, so that the transmitted tones are subject to somewhat less alteration than otherwise. I find that any departure from the right-angle arrangement of these walls, with respect to the general plane of the vibrator, results in a corresponding diminution of their utility. I have secured good results by fixing short paper tubes at close intervals over the surface of the vibrator. I prefer that the walls B be made of card-board or thin wood—such as veneer. C and D are the resistance-varying contact-points or electrodes essential to a battery transmitting-telephone, the contact C being borne by the acoustic vibrator A, and the contact D being carried by an arm, D', which arm is suspended from above, by preference, like the vibrator, though it may be hinged at the side or below. It is hung or connected at such a point that the force of gravity will cause it to rest lightly against the contact C. I prefer that the arm D' and vibrator A be both hinged at or suspended from the same point in order that the bodily back-and-forth movement or swinging of the vibrator will not cause the two contacts to rub against or rasp across each other, as would be the case were they hung from different points. This suspended contact D requires no adjustment whatever, being arranged to touch the contact C with the requisite pressure at first, and thereafter being unaffected by changes of temperature or the varying positions of the vibrator.

The contacts C and D may be of any suitable material having the proper degree of resistance to the passage of an electric current—such as carbon, platina, &c.

A wire, c, leads from the contact C, and another wire, d, leads from the contact D, both wires forming part of the usual local battery-circuit used with transmitters.

A telephone as sensitive as mine is apt to be affected by the jarring of the building, and by echoes to such an extent as to detract from the clearness of its transmission of speech. To overcome this defect I have designed the mounting for the telephone, which I will now describe.

The vibrator A and arm D' are suspended from an inert body, E, or one having considerable weight in proportion to its bulk, which is itself supported through the medium of an elastic connection, F, preferably of soft india-rubber. The vibrations affecting the supporting part are not communicated to the body E because of its sluggishness or inertia, but are absorbed before reaching it by the elastic substance F.

G is an inclosing case or box surrounding

the active elements of the telephone, and designed to cut off all sounds proceeding from other directions than in front of the vibrator, at which point it is furnished with an opening, G'. It may be made of wood or other suitable material. The active elements of the telephone are suspended or arranged inside of it.

H is a muffling-lining of non-vibratory or sound-deadening material—such as cotton-wool, felt, soft rubber, &c.—whose office is to prevent the reflection of sound-waves against the sides of the box, thereby suppressing echoes.

I will now more specifically describe the particular constructions shown in the drawings.

Referring first to Figs. 1 to 4, the acoustic vibrator A is in disk form, with a rectangular top for convenience of attaching hinge-leaves a a, which engage a horizontal pin or rod, b, fixed to the body E. By this means the vibrator is pendulously suspended, and is free to swing bodily backward and forward. The walls B extend around the vibrator and cross it in two directions, vertically and horizontally. The contact C is held in a cup fixed to the back of the vibrator, and the contact D is held in a similar cup formed at the lower end of the arm D', whose upper end engages the rod b between the hinge-leaves a a. The body E consists of a piece of heavy metal tubing fitted on a rod whose ends project beyond it, and having downwardly-projecting ears for engaging the ends of the rod b. The prolonged ends of the upper rod are each engaged by an elastic connection, F, which is a suspending connection consisting of a rubber ring or band, although a piece of soft twine or a very elastic spiral spring might suffice. The connections F F hang from hooks f f, which are secured to the case G. I prefer to set this case on a non-vibratory pad or layer, g, shown in Fig. 1, to prevent the jarring of the building or of the shelf or table on which it may rest from being communicated to it. A telephone of this construction is so sensitive to vocal sounds that ordinary conversation uttered in distant parts of a large room in which it is placed are reproduced in the receiving-telephone at a distant station with perfect distinctness, while at the same time it is so free from microphonic effects that it is not at all influenced by the rumblings and jarrings of the building in which it is placed. The transmission of sound is clear and natural, and the speaker need not be stationed close to the instrument.

In Figs. 5 to 8 two sets of contacts, C D, are shown. The effect is not materially different from that of one pair of contacts, but in some instances their use may be desirable. In Fig. 7 the circuit is shown as divided into two branches, with one pair of contacts in each branch, and in Fig. 8 the two pairs are arranged successively in the undivided circuit. The former plan secures a somewhat louder sound in the receiving-instrument than when but one pair of contacts is used, and there is less re-

sistance to the passage of a feeble current, while the latter plan transmits a more natural but somewhat fainter sound. In these figures the acoustic vibrator is a plain flat polygonal board of thin wood, and the walls B are separate from it, being borne by the case G and projecting in from the opening G'. The vibrator A and rigid arms D' are all hung from the inert body E by means of strips of light flexible material, as shown in Figs. 5 and 6. The body E is a simple bar of heavy metal, its ends resting on soft yielding cushions of rubber or similar substance, which are the elastic connections F F, and these rest on shelves or cleats 15 fixed to the sides of the case.

Fig. 9 shows also two pairs of contacts, but arranged differentially instead of cumulatively, one pair being on each side of the vibrator, and each pair being in a separate circuit or 20 branch, with a separate battery in each branch. The undivided portion of the circuit includes the primary wire of an induction-coil, I, and the line or earth circuit includes the secondary wire thereof, as usual. The arrangement of 25 batteries and circuits is such that when the vibrator A moves or vibrates in one direction and presses together one pair of contacts it sends a current through the induction-coil in one direction, whereas when it moves or vibrates in the opposite direction and presses 30 together the other pair of contacts it sends a current in the opposite direction through the coil. When it is not in vibration the two opposite currents will in effect neutralize each 35 other, and as one current is strengthened by the movement of the vibrator the other current is correspondingly weakened. This arrangement is not new with me; but my telephone is especially adapted for this method of 40 connection, inasmuch as its contacts are self-adjusting, whereas heretofore it has been almost impossible to properly adjust the two pairs of contacts relatively to each other and to a fixed diaphragm, and the adjustment, 45 when secured, has been liable to derangement by changes of temperature and other causes.

Instead of using two batteries and one induction-coil one battery and two induction-coils may be employed, one coil and one pair 50 of contacts being in each branch of the circuit and the battery in the undivided portion. The line-circuit will then pass successively through both coils.

I make no claim in this application to the 55 combination of this reverse-current arrangement with the peculiar features of my telephone, as I contemplate making such claim the subject of a future application for patent.

I make no specific claim in this application 60 to the novel features involved in the modified forms of my invention, but I contemplate covering such features by future applications.

I claim as my invention—

1. The acoustic vibrator or diaphragm of a 65 telephone, unmuffled and unconfined, and hung or suspended from above and otherwise un-

supported, whereby it is capable of swinging pendulously and of vibrating over its entire surface, substantially as set forth.

2. An acoustic vibrator or diaphragm for a 70 telephone consisting of a plate of thin resonant wood suspended from above and capable of swinging backward and forward.

3. In a transmitting-telephone, an acoustic vibrator or diaphragm consisting of a vibrating plate supported flexibly at one edge, having its remaining edges unconfined and unmuffled, and bearing upon its back one of the resistance-varying contacts or electrodes, substantially as set forth. 80

4. In a transmitting-telephone, the combination of an acoustic vibrator or diaphragm, A, supported flexibly at one side or edge and otherwise unsupported, and capable of bodily movement backward and forward, with sound 85 confining and reflecting walls B, arranged in front of said vibrator and at substantially right angles to the general plane thereof.

5. An acoustic vibrator or diaphragm for a telephone, flexibly supported at one edge or 90 side and otherwise unsupported, so as to be capable of swinging to and fro, and provided with sound receiving and confining walls fixed to and borne by it and arranged at substantially right angles to the general plane of its 95 surface.

6. An acoustic vibrator or diaphragm for a telephone, flexibly suspended from above and provided on its front surface with light sound collecting and confining walls or partitions 100 fixed to it at substantially right angles to the general plane of its surface.

7. An acoustic vibrator for a telephone consisting of a board of light resonant wood suspended flexibly from above and otherwise unsupported, and provided with sound-confining walls or partitions of light material, as cardboard or veneer, fixed to it at right angles, or nearly so, substantially as set forth. 105

8. A transmitting-telephone consisting of 110 an acoustic vibrator supported flexibly at one side and bearing a resistance-varying contact or electrode, in combination with another such contact or electrode, the two contacts being pressed lightly together by the force of gravity, 115 substantially as set forth.

9. A transmitting-telephone consisting of the combination of a suspended vibrating plate capable of swinging back and forth, a resistance-varying electrode arranged against the 120 back thereof, and a second such electrode borne by a part which is also hung or suspended from above, pressed gently against the first electrode by the action of gravity and capable of swinging with the vibrating plate, substantially as set forth. 125

10. A transmitting-telephone consisting of an acoustic vibrator or diaphragm supported at one side or edge and otherwise unsupported, and free to vibrate and to move bodily back 130 and forth, and bearing a resistance-varying contact, in combination with another such con-

tact arranged to lightly touch the first and borne by a part which is supported from the same point as the vibrator, substantially as and for the purposes set forth.

5 11. The combination of the acoustic vibrator or diaphragm and resistance-varying contacts of a transmitting-telephone with an inert body, E, arranged to support said parts, and with elastic connections F F, arranged to support 10 said body, whereby said vibrator and contacts are insulated from inaudible vibrations affecting the ultimate support of the apparatus, substantially as set forth.

12. The combination of the acoustic vibrator 15 or diaphragm and resistance-varying contacts of a transmitting-telephone, with elastic or sound-absorbing suspending connections F F, substantially as and for the purposes set forth.

13. The combination of the acoustic vibrator 20 and resistance-varying contacts of a transmitting-telephone, with a box or case, G, arranged

to inclose the same, and a sound absorbing or muffling lining, H, covering the interior surface of the case and arranged out of contact with the vibrator, for the purposes set forth. 25

14. The combination of a box or case, G, having a sound-opening, G', a sound absorbing or muffling lining, H, arranged to cover substantially the entire interior surface of the case, and the acoustic vibrator or diaphragm 30 and resistance-varying contacts of a transmitting-telephone suspended freely within the case and arranged out of contact with said lining, substantially as set forth.

In witness whereof I have hereunto signed 35 my name in the presence of two subscribing witnesses.

WM. MAIN.
